UNITED STATES PATENT OFFICE.

WILLIAM R. DAWSON, OF EAST LIVERPOOL, OHIO.

SAWING APPARATUS.

1,108,718.

Specification of Letters Patent.

Patented Aug. 25, 1914.

Application filed March 24, 1913. Serial No. 756,301.

To all whom it may concern:

Be it known that I, WILLIAM R. DAWSON, a citizen of the United States of America, and resident of East Liverpool, county of Columbiana, and State of Ohio, have invented 5 certain new and useful Improvements in Sawing Apparatus, of which the following is a specification.

This invention relates broadly to improvements in sawing apparatus, and specifically to a machine for sawing steel rails and the like.

The primary object of the invention is to provide a portable machine whereby railway track rails may be conveniently and expeditiously sawed, as when it is desired to remove a section of such rail.

A further object is to provide a sawing apparatus adapted to be actuated either by hand power or by a small portable electric motor, and the operation of which, when actuated by hand, is accomplished with a minimum of fatiguing labor. And a still further object is to provide a hack-saw 25 adapted for oscillatory movement.

With these and other important objects in view, the invention resides in the features of construction, arrangement of parts and combinations of elements which will 30 hereinafter be exemplified, reference being had to the accompanying drawings, forming a part of this specification, in which—

Figure 1 is a side elevation of the invention applied to the sawing of a railway rail; 35 Fig. 2 is a top plan view of the same; Fig. 3 is a rear end view; Fig. 4 is a transverse vertical section on the line 2—2, Fig. 2; and Fig. 5 is a horizontal section on the line 5—5, Fig. 4.

40 Referring to said drawings, in which like designating characters distinguish like parts throughout the several views—1 and 2 indicate the opposite track rails of a railway track, the former being that which, as here- 45 in depicted, is to be acted upon, as for detaching a section thereof. Mounted over said rail 1, and supported in a manner which will hereinafter be exemplified, are two upright parallel members 3 and 4 which serve 50 as guides for an interposed head-piece 5. Said head-piece is supported by and is vertically movable upon a vertically-disposed feed-screw 6 which is rotatably mounted in a suitable collar-like bearing 7 rigidly 55 mounted between the upper ends of said members 3 and 4. The member 3 is pro-

vided with a vertically disposed slot 3^a through which projects a spindle 8 which is fixed in the head-piece 5. Rotatable upon the projecting portion of said spindle 8 is 60 a pinion 9 in mesh with a gear wheel 10 which is mounted in fixed relation to an oscillatory hack-saw, generally designated by the numeral 11, said hack-saw comprises a bow-shaped member, which may be constituted by a pair of oppositely disposed inclined arms 12 joined to a hub 13, and an arcuately curved saw-blade 14 carried by said bow-shaped member, said blade having its opposite ends detachably connected to 70 the opposite ends of said member, or to the lower ends of said arms 12. The said gear wheel 10 is preferably fixed, as shown, upon an inwardly directed reduced end provided on the hub 13, which latter is mounted to 75 oscillate on a spindle 15 fixed in the head-piece 5 below the spindle 8.

As is apparent, the head-piece 5 is lowered by turning a hand-wheel 16 fixed on the feed-screw 6 until the saw-blade 14 assumes 80 operative engagement with the rail 1. Then, by rocking movement of a hand-lever 17 having fixed relation to the pinion 9; oscillatory movement is communicated to said hack-saw. The blade 14 has a curvature corresponding to the arc of a circle whose center is the axis of the spindle 15; consequently, the entire length of the oscillatory stroke is utilized. As the sawing operation progresses, the saw is gradually 85 advanced, or lowered, into the work by manipulation of the feed-screw 6.

For rigidly supporting in working position the parts hereinbefore described, I provide a frame which may be of any appropriate character, but which, owing to its comparative simplicity and cheapness, is preferably of the type exemplified in the drawings, in which 18 designates a base-member having feet 18^a adapted for resting 100 upon the head of rail 1 and having rigidly mounted thereon the upright parallel members 3 and 4 hereinbefore referred to. Rigidly connected to said base-member 18, as by mounting their ends in sleeve-like eye- 105 portions 19 formed in the latter, is a pair of parallel rods 20, preferably formed of gas-pipe, which extend transversely across the line of track and have their opposite ends received in sleeve-like eye-portions 21 110 formed in a member 22 which is adjustable along said rods and is adapted to rest upon

the track-rail 2. Said member 22 has lugs or a flange 23 formed laterally of its under face and adapted for seating firmly against the inner surface of the head of rail 2 when said member occupies adjusted position, being secured in such position by set-screws 24. Similar lugs 25 are provided on the base-member 18 for seating against the inner surface of the head of rail 1, and dogs 26 adjustably mounted on the rod-ends which project outward from the eye-portions 19 are adapted to be set by means of set-screws 27 in clamping engagement with the outer surface of the head of rail 1 in opposing relation to the lugs 25. Connecting the rods 20 at a suitable point between the track-rails 1 and 2 is a brace-rod 28, and fixed to the latter are the lower ends of suitably curved brace-rods 29 which have their opposite ends received and firmly held in bearing-like eye-portions 30 formed at the upper ends of the members 3 and 4.

While I have described my invention more or less in detail, it will be obvious that 25 various mechanical changes may be resorted to without departing from the general spirit or scope of the invention as defined in the appended claims.

Having thus described my invention, what 30 I claim as new, and desire to secure by Letters Patent, is—

1. An apparatus for sawing railway track rails, comprising a base-member adapted for resting upon the head of a rail, means for 35 clamping said base member on said rail, a pair of rods connected to said base-member and extending across to the opposite track rail, means adjustably mounted on said rods for assuming clamping engagement with

said opposite track rail, a pair of upright members mounted on said base-member, means disposed between said rods and said upright members for bracing the latter, a vertically movable head-piece disposed between said upright members, means for raising and lowering said head-piece, an oscillatory hack-saw carried by said head-piece, and means for communicating oscillatory movement to said saw.

2. An apparatus for sawing railway track 50 rails, comprising a base-member adapted for resting upon the head of a rail, means for clamping said base-member on said rail, a pair of rods connected to said base-member and extending across to the opposite track 55 rail, means adjustably mounted on said rods for assuming clamping engagement with said opposite track rail, a pair of upright members mounted on said base-member, means disposed between said rods and said upright members for bracing the latter, a vertically movable head-piece disposed between 60 said upright members, means for raising and lowering said head-piece, a spindle carried by said head-piece, a hub mounted on said spindle, inclined oppositely disposed arms formed on said hub, an arcuately curved saw blade having its ends attached to said arms, a lever pivotally mounted on 65 said head-piece, and means whereby power applied to said lever effects the oscillation of said hub.

In testimony whereof, I affix my signature in presence of two subscribing witnesses.

WILLIAM R. DAWSON.
